INVENTOR:

P. Tenney Gates

by his Attorney,

W. G. Johnston

UNITED STATES PATENT OFFICE.

PHILEMON TENNEY GATES, OF NEW YORK, N. Y.

PARER, SLICER, AND CORER.

SPECIFICATION forming part of Letters Patent No. 339,542, dated April 6, 1886.

Application filed October 29, 1885. Serial No. 181,215. (No model.)

To all whom it may concern:

Be it known that I, PHILEMON TENNEY GATES, a citizen of the United States, and a resident of New York, in the county of New York and State of New York, have invented certain new and useful Improvements in a Parer, Slicer, and Corer for Fruit and Vegetables, of which the following is a specification.

10 The invention relates to an instrument which has all the uses of a parer, a slicer, a corer, and a speck-remover.

By a diligent and systematic study in the application of the principles of the science of invention, and by trials of successively improved devices, I have succeeded in effecting such important improvements that the device is at once adapted to meet the wants of all concerned in a very effectual and superior manner, which is the main object sought to be accomplished.

25 The invention has the specific object of providing an instrument embodying a combination which shall be so useful and convenient that all housekeepers shall desire to be in possession of the same.

30 My invention primarily consists of a handle, provided with a parer, slicer, and speck-remover, all constructed in one piece and secured to said handle, and of a coring-ring, also

35 In order to illustrate the practical manner of carrying out the invention, and to enable others to construct and use the same, drawings are hereunto annexed and described, in which similar characters of reference represent corresponding elements.

Figure 1 is a general view of three of the instruments packed in a box. Figs. 2, 3, 40 and 4 show some applications of the instrument.

45 The device embodying my invention consists of the combination of a blade, A, of sheet metal, bent into two longitudinal grooves, as shown in the drawings, to form a cutting-edge, B, and having a longitudinal slot, C, cut out along the crown or bend D of the blade, forming a discharge-opening having curved ends, C', a speck-remover, E, upon the end of the

blade, the above named elements being formed 50 of but a single piece of metal, a handle, F, a coring-ring, G, having cutting-edges G'—one upon one or both sides of the ring—and located upon said handle, a slot, H, and hole, I, (shown dotted,) in one end of said handles, 55 projections K and L to said ring, the former being longer than the other and provided with a hook, M, and pins N and N', passing through said handle, the former passing within said hook and the latter at the end of the projection L.

In Fig. 2 the speck-remover is represented as removing a speck from the potato O, while P represents the conical hole left by the removal of a speck.

65 Fig. 3 shows the ring in the act of removing a decayed portion, Q, leaving a hole similar to R.

70 Fig. 4 shows the ring removing a core, S, from the fruit T.

I lay no claim to the shape of the knife-blade or parer, as such a shape is shown in Brock's Patent No. 297,748, April 29, 1884, (apple parer and slicer,) assigned to me on or about October 30, 1884, the assignment having 75 been duly recorded at the Patent Office.

7C What I claim is—

1. A combined parer, slicer, and corer, consisting of a blade, A, of sheet metal, bent or creased longitudinally, as described, to form 80 a cutting-edge, B, and having a longitudinal slot, C, cut out along the crown or bend D of the blade, forming a discharge-opening, a speck-remover, E, upon the end of the blade and integral therewith, a handle, F, to said 85 blade, and an adjustable coring-ring, G, upon the handle, substantially as described.

2. A combined parer, slicer, and corer, consisting of the blade A, of sheet metal, bent or creased longitudinally, as shown in the drawings, to form a cutting-edge, B, and having a longitudinal slot, C, cut out along the crown or bend D of the blade, forming a discharge-opening having curved ends C', a speck-remover, E, upon the end of the blade, 95 the above-named elements being composed of but a single piece of metal, a handle, F, a coring-ring, G, to said handle, a slot, H, and

hole I in said handle, projections K and L to said ring, the former being longer than the other, and provided with a hook, M, and pins N and N', passing through said handle, the former passing within said hook and the letter at the end of the projection L.

In testimony that I claim the foregoing as

my invention I have signed my name, in presence of two witnesses, this 16th day of October, 1885.

PHILEMON TENNEY GATES.
Witnesses:

CHARLES P. HOUSUM,
EDWARD P. THOMPSON.
